(57) **CLAIM**

The ornamental design for a dental implant fixture mount, as shown and described.

DESCRIPTION

FIG. 1 is a top plan view of a dental implant fixture mount showing our new design, the bottom plan view being a mirror image of the plan view shown;

FIG. 2 is a left side elevational view thereof;

FIG. 3 is a right side elevational view thereof;

FIG. 4 is a top plan view thereof, the bottom plan view being a mirror image of the plan view shown; and,

FIG. 5 is a cross-sectional view thereof taken along line A—A in FIG. 3.
